UNITED STATES PATENT OFFICE.

THOMAS WESLEY HOLLEY, OF RANGER, TEXAS.

WELL-DRILLING RIG.

Original application filed February 10, 1921, Serial No. 444,030. Divided and this application filed May 18, 1922. Serial No. 561,927.

To all whom it may concern:

Be it known that I, THOMAS W. HOLLEY, a citizen of the United States, residing at Ranger, in the county of Eastland and State 5 of Texas, have invented certain new and useful Improvements in Well-Drilling Rigs, of which the following is a specification.

This invention relates to well drilling rigs and is a division from my co-pending application filed February 10, 1921, Serial No. 444,030 and the primary object of the invention is to provide a novel means for constructing and arranging the sand reel supporting pedestal and control mechanism upon the standard rig, said means cooperating with the standard rig to permit the adjustment of the sand reel and control mechanism, to suit varying conditions and to eliminate the usual difficulties experienced in 15 associating the pedestal with the rig and the wear on the pedestal.

It is now common practice to support the sand reel by a shaft received at one end by a tail post and at its other end by a lever 20 carried by the knuckle post, the lever being manually actuated by a sand reel handle and reach connecting the handle and lever. The pedestal or knuckle post is rigidly connected with the main sill by cutting a notch 25 or gain therein for receiving the knuckle post, which not only materially weakens the main sill, but prevents adjustment of the knuckle post in relation to the band wheel.

Further the lever, in the usual construction 30 is generally made of wood and receives the end of the sand wheel shaft. The hole in the lever for the sand wheel shaft rapidly enlarges making necessary replacement of the pedestal or lever which takes time and 35 is a considerable expense when replacement is frequently required.

It is therefore, a prime object of the invention to provide a novel pedestal, and a novel means for mounting the pedestal upon 40 the main sill whereby the notching of the main sill is eliminated, and whereby adjustment of the pedestal longitudinally of the sill is permitted, so as to allow initial adjustment of the sand reel in relation to 45 the band wheel.

A further object of the invention is to provide a novel support for one end of the sand reel shaft adjustably mounted within the pedestal, so that the sand reel can be 50 finally adjusted in relation to the said band

wheel, novel provision being also made to permit adjustment of the novel control mechanism for the sand reel.

A still further object of the invention is 60 to provide an improved device of the above character, which will be durable and efficient in use, one that will be simple and easy to manufacture, and one which can be associated with an ordinary standard rig. 65

With these and other objects in view, the invention consists in the novel construction, arrangement and formation of parts, as will be hereinafter more specifically described, claimed and illustrated in the accompanying 70 drawings, forming a part of this specification, in which drawings:

Figure 1 is a side elevation of a portion of the wheel drilling rig showing a pedestal and reel controlled mechanism constructed 75 in accordance with this invention applied thereto.

Figure 2 is a plan view of the sand reel portion of the rig.

Figure 3 is a detail view partly in elevation and partly in vertical section of the reel and a portion of the control mechanism.

Figure 4 is an enlarged sectional view on the line 4-4 of Figure 1 of the drawings.

In the drawings, where similar characters 80 refer to similar parts throughout the views, A designates the main sill, B the sub sill, C the sand reel tail sill and D the mud sills of the rig; E the sand reel, F and G its shaft and pulley respectively; H the band wheel 90 for engagement with pulley G; and J the derrick floor all of which may be of the usual or any preferred construction. The one end of shaft F may be supported by a tail post or pedestal of the usual construction but 95 in the example shown is supported by a pedestal K of the character disclosed in my co-pending application for patent filed on the tenth day of February, 1921, Serial Number 444,029. The present invention is 100 designated by L as to the pedestal and M as to control mechanism for the reel.

The invention is herein shown as applied to what is commonly known as the standard rig, in which the sand reel shaft F is disposed with its axis extending diagonally crosswise the plane of band wheel H, but it is to be understood that the principle of this invention may be applied to other types of rig, without departing from the spirit of 110 the invention. It is understood that, in

practice, the sand reel E is used for the purpose of lowering and raising a sand pump or bailer, not shown in the drawings, as by use of a cable 5, and this is accomplished by 5 moving the shaft F so that the pulley G is moved into and out of engagement with the band wheel H.

The particular type of pedestal or tail post K, shown in Figure 2 of the drawings 10 does not form a part of the present invention, but is more specifically disclosed in my co-pending application for patent hereinbefore referred to. It is shown merely by way 15 of example to indicate that the shaft F, when moved, for bringing the pulley G into and out of engagement with the band wheel H, pivots in bearing 6 of the pedestal K.

The pedestal L comprises, broadly, a base 20 7, a frame 8, and a bearing block 9 slideable in frame 8. The base 7 has means 10 for securing the base to the main sill A of the rig, so that it may be adjusted longitudinally of the sill, or in other words, in a plane parallel to the plane of band wheel H. 25 The frame 8 has means 11 for securing it to the base 7 and permitting adjustment of the frame toward or from the plane of the band wheel H.

The base 7 in the example shown 30 comprises a pair of base bars 12 arranged in parallel spaced apart relation, and a connection 13, such as a piece of timber which is secured to the under side of the bars 12, and which may be secured to the bars in 35 any suitable manner, such as by bolts 14 and nuts 15. The base bars 12 are preferably formed of rolled angle section, thus providing a horizontally disposed flange 16, and vertically disposed flanges 17. For a purpose 40 to be subsequently set forth there is provided adjacent each end of flange 16, a perforation 18, and the vertical flanges 17 are each provided with a series of perforations 19 arranged longitudinally of the flange. The base 7 may also comprise one 45 or more filler pieces 20, which may be interposed between the connections 13 and the base sill A in order to dispose the base bars 12 at the desired distance above the upper 50 face of the main sill, these filler pieces being preferably arranged directly beneath the base bars, as clearly shown in Figure 1 of the drawings.

The means 10 for securing the base to the 55 main sill may comprise clamp bars 21 adapted to engage the under side of sill A, and take up devices 22, which latter may each be in the form of a rod 23 screw threaded at opposite end portions, and nuts 24 in screw 60 threaded engagement with these end portions. Each clamp bar is provided adjacent its end portions with perforations 25, there being one clamp bar for each base bar, the perforations 25 being aligned with 65 the perforations 18 in the base bar. The

rods 23 are thus accommodated in the perforations 18 and 25, and by turning the nuts 24 tight, the base 7 may be secured to the base sill against longitudinal and lateral movement with respect thereto. The base 70 may be adjusted, however, longitudinally of the sill, as is obvious from the foregoing, it being necessary to merely release some of the nuts 24 and shift the base 7 longitudinally of the sill. 75

The frame 8, in the example shown, comprises a pair of uprights 26, in spaced apart relation, and horizontal guide members 27 secured to the uprights 26 in spaced apart relation. The uprights 26 may be conveniently formed from rolled channel sections, one of which is provided with a vertical slot or opening 28 for a purpose to be subsequently set forth. The guide members 27 may be substantially H shaped in cross section, whereby each member is provided with parallel flanges 29, serving to hold the bearing block 9 against movement laterally of the frame. The guide members may be secured to the uprights, in any suitable manner, such as by bolts and nuts 30 and 31 respectively. 80 85 90

Referring now to the means 11 for securing the frame 8 to the base 7, permitting adjustment of the frame toward or from the plane of the band wheel H, such may consist merely of bolts 32 and nuts 33, although it is desirable to also provide braces 34, connected to the upper portion of the frame as by one of the bolts 30 and nuts 31, and to the base bars as by bolt 34' and nut 35, these braces acting as struts, since most of the pressure incident to operation of the sand reel, is outwardly, the bearing block 9 acting somewhat as a thrust bearing where a beveled pulley G is used. The shanks of bolts 32 may be extended through any selected perforations 19, these perforations permitting of adjustment of the frame 8 toward or from the plane of the band wheel H. 100 105 110

Bearing block 9 may be formed of a single piece of metal, or may be built up in any suitable manner, it sufficing to show, in the example shown, that the block is provided with an opening 36 for the reception of shaft F, a lining of Babbitt metal or its equivalent 37, being provided in said opening, and the block also having grooves 38 at its upper and lower faces for the reception of the flanges 29. While but slight movement of the block is necessary to bring the pulley G into and out of engagement with the band wheel H, the frame 8 is made relatively long so that it is possible to move the bearing block 9 a considerable distance in either uprights 26. This has a material advantage as will be noted hereinafter, since it is not always possible to clamp the base 7 to the main sill in a manner that the shaft E is accurately positioned for engage- 115 120 125 130

ment of the pulley G with the band wheel H, by operation of the mechanism M.

The mechanism M comprises, an arm 40 extending from one end of frame 8; a lever 41 in the example shown, pendently supported by arm 40; a link 42 connecting bearing block 9 and lever 41; an arm 43 extending from base 7 in the same direction as arm 40; a lever 44 pivotally connected to arm 43 at one end and to lever 41 intermediate its ends; a sand reel lever 45 on platform J adapted to be manually actuated; and a reach 46 operatively connecting levers 44 and 45, so that when movement is imparted to lever 45 it will be transmitted through reach 46, lever 44, lever 41 and link 42, to the bearing block 9. It is preferred to provide the arm 40 with a plurality of perforations 47 longitudinally thereof, and to provide a plurality of perforations 48 in spaced apart relation longitudinally of lever 41. Also link 42, may be provided with a plurality of perforations 49, so that the connecting device 50, such as a bolt, which pivotally connects the lever 41 to arm 40 may be disposed in any of the perforations 47 and 48 selected, for adjustment. Likewise connecting device 51 for the link 42 and lever 41 may be passed through any of the selected perforations 48 and 49, for adjusting purposes, as hereinafter noted. The arm 43 and lever 44 is provided mainly to permit of disposing the sand reel operating lever 45 in the belt house or well within the margins of the platform J, and so as to avoid engagement of the reach 46 with a standard 52 of the band wheel H, which is usually a stock feature. The connection between lever 44 and arm 43 may be by means of a pin or bolt 53 extending through an elongated slot 54 in the end portion of lever 44. The reach 46 may be made up of a plurality of sections detachably and adjustably connected, as indicated at 55, and the end portion of the reach adjacent lever 45 may be provided with a plurality of perforations 56, any one of which may be aligned with any one of a plurality of perforations 57 in lever 45, a bolt 58 serving to pivotally connect the lever with the reach.

It is to be noted that the perforations 47, 48 and 49 permit a wide range of adjustment as to the relative position between the bearing block 9 and the operating lever 45. The relatively long guide bars 27 enable the workmen to quickly assemble the pedestal into operative relation to the main sill by use of means 10, accurate adjustment at such time not being necessary. When assembling the shaft into operative relation with the bearing block 9, the entire frame 8 may be moved toward or from the complementary pedestal K, according to the length of the shaft to be accommodated, this being possible because of the provision of means

11. After the mechanism has thus been assembled, it is desirable to adjust the mechanism so that the pulley G will have good frictional contact with the band wheel H, so as to not wear the latter. This may be accomplished by either adjusting the pedestal K, or by adjustment of the mechanism M. The link 42 extends through the opening 28 in upright 26, which opening is of sufficient size to permit the link to swing in- 75

76 to movement of lever 41. From the foregoing description, it can be seen that a novel well drilling rig has been provided in which the pedestal for the sand reel can be adjusted longitudinally of the main sill of the rig in a novel manner and the bearing for the sand reel shaft adjusted in respect to the pedestal both longitudinally and laterally with respect to the band wheel, and novel means for permitting adjustment of the novel control mechanism for the sand reel.

Changes in details may be made without departing from the spirit or scope of this invention; but,

I claim:

1. In a well drilling rig, the combination of a main sill and a tail sill, a sand reel including a shaft and pulley, and a band wheel for engagement with said pulley, of a tail pedestal for one end of said shaft carried by the tail sill, a head pedestal mounted upon the main sill for longitudinal movement, a bearing for the other end of the sand reel shaft associated with the pedestal for movement longitudinally and laterally of the main sill, a manually operated means for adjusting the bearing block longitudinally of the main sill, and means for permitting adjustment of the operating mechanism relative to the adjustment of the head pedestal and of the bearing block laterally of the main sill.

2. In a well drill rig, the combination with a main sill and a tail sill, a sand reel including a shaft and pulley, a band wheel for engagement with said pulley and a tail pedestal for one end of said shaft carried by said tail sill, a head pedestal mounted upon said main sill including a frame adjustable longitudinally of said main sill and a horizontally movable bearing block carried by said frame, an arm carried by said frame projecting from one end thereof and having a portion provided with a plurality of perforations and arranged in a plane coincident or parallel to the plane of movement of said bearing block, a lever provided with a plurality of perforations arranged longitudinally thereof, means pivotally connecting said lever to said arm, said means including an element passing through selected perforations of said arm and lever for adjusting purposes, a link pivotally connected to said bearing block at one end and

2
provided with a plurality of perforations at its other end, means for pivotally connecting said link to said lever including a device passing through selective perforations of said link and lever for adjusting purposes, and means for actuating said lever at a point remote from said pedestal.

3. In a well drilling rig, the combination with a main sill and a tail sill, a sand reel 10 including a shaft and pulley, and a band wheel for engagement with said pulley, of a tail pedestal for one end of said shaft carried by said tail sill, a head pedestal mounted upon said main sill including a frame adjustable longitudinally and transversely of said main sill and a horizontally movable bearing block carried by said frame for the other end of the shaft, an arm carried by said frame projecting from one end thereof, a lever, means pivotally and adjustably

connecting said lever to said arm to depend therefrom, a link, means pivotally connecting one portion of said link to said bearing block, means pivotally and adjustably connecting the other end portion of said link to said lever, a second arm carried by said frame arranged below said first arm and to one side of the vertical plane thereof, a lever pivotally connected to said second arm and extending near said first mentioned lever and operatively connected thereto at its intermediate portion whereby movement of said second mentioned lever will be imparted to said bearing block through said first mentioned lever and link, a sand reel lever remote from said pedestal, and a reach connecting said sand reel lever and the free end portion of said second mentioned lever. 25 30 35

THOMAS WESLEY HOLLEY.
